UNITED STATES PATENT OFFICE.

JOHN SCHULLER, OF BROOKLYN, NEW YORK.

DESIGN FOR A MILITARY CAP.

Specification forming part of Design No. 5,834, dated April 30, 1872.

Specification describing a new and original Design for a Military Cap, invented by JOHN SCHULLER, of Brooklyn, in the county of Kings and State of New York.

Figure 1 represents a side view, and Fig. 2 a front view of my new design for a cap.

Similar letters of reference indicate corresponding parts.

This invention relates to a new configuration of a military cap.

The cap is made higher in front than behind; has a rounding crown, *a*, which is, by an undulating projecting border, *b*, separated from the side or body *d*, which is slightly inclined, as shown. The lower band *e* is narrow in front,

but considerably wider behind. The front ornament *f* of the cap consists of a circle of balls, which is surrounded by radiating spear-heads, cannons, and rays, as shown. The central circular space of the ornament *f* is to receive the regimental number, or initials, or other mark indicating the name or character of the troop. This front ornament, however, does not constitute part of this invention.

I claim as my invention—

The design for a military cap, as shown.

JNO. SCHULLER.
